Attorney.

UNITED STATES PATENT OFFICE.

CHARLES HARRIS JOHNSON, OF CHICAGO HEIGHTS, ILLINOIS, ASSIGNOR TO
THE JOHNSON, PARFITT TOOL COMPANY, OF SPRINGFIELD, ILLINOIS.

PNEUMATIC HAMMER.

SPECIFICATION forming part of Letters Patent No. 655,902, dated August 14, 1900.

Application filed January 31, 1900. Serial No. 3,506. (No model.)

To all whom it may concern:

Be it known that I, CHARLES HARRIS JOHNSON, a citizen of the United States, residing at Chicago Heights, in the county of Cook, State 5 of Illinois, have invented certain new and useful Improvements in Pneumatic Hammers and Like Tools Operated by Fluid-Pressure; and I hereby declare the following to be a full, clear, and exact description of the same, 10 reference being had to the accompanying drawings, in which—

Figure 1 is a longitudinal central section of a pneumatic tool embodying my invention. Fig. 2 is a longitudinal central section of the 15 cylinder, the piston, &c., removed. Fig. 3 is an end view of the tool looking in the direction of the arrow, Fig. 2. Fig. 4 is an end and Fig. 5 a sectional view of the piston. Fig. 6 is a sectional view, and Fig. 7 an end 20 view, of the annular end plug of the cylinder. Fig. 8 is an end view, and Fig. 9 a side elevation, of the movable block or button which is struck by the piston or hammer and delivers the blow to the tool proper. Fig. 10 is a 25 sectional view, and Fig. 11 is an end view, of the ferrule or bushing of the plug and which holds the tool proper.

Like symbols refer to like parts wherever they occur.

30 My invention relates generally to that class of motive-fluid-operated tools wherein are combined a cylinder and piston, the latter constituting the hammer which delivers the blow either meditately or immediately to the 35 special tool carried by or inserted in the cylinder or case wherein the piston or hammer reciprocates, and especially to that class commonly termed "valveless," wherein a differential piston or a piston of different area on 40 opposite ends is employed, and has for its object to eliminate from the construction ports or passages within the walls of the cylinder, whereby a greatly-simplified and thoroughly-effective tool is obtained.

45 To this end the main feature of my invention, generally stated, embraces the combination, with a suitable cylinder having an annular groove or channel on its interior and an exhaust-port of a differential piston hav-

ing non-communicating passages leading 50 from its opposite ends and which communicate with each other through the annular groove or channel on the interior of the cylinder, said cylinder having a motive-fluid-supply port arranged to maintain a constant 55 pressure on that head of the piston having the lesser area, whereby the reciprocation of the piston is effected.

There are other minor features of invention, all as will hereinafter more fully appear. 60

I will now proceed to describe my invention more fully, so that others skilled in the art to which it appertains may apply the same.

1 indicates the tool case or cylinder, formed on its interior with the two bores 2 and 3 of 65 different diameters, with the lesser of which, 2, the induction-port 4 for the admission of the motive fluid communicates, so that a constant pressure is maintained on the piston-head of lesser area during the operation of 70 the devices.

At some suitable point in the motive-fluid-induction passage or pipe a suitable throttle-valve T is located. In the present instance one of a particular construction—viz., a plug 75 or piston of different diameters—has been chosen for illustration; but the same is not herein further described, as it forms no part of the present application, being reserved for the subject-matter of a separate application, 80 and it is to be understood that any suitable throttle-valve which will control the induction-passage of the tool may be substituted for the one shown in the drawings.

At or adjacent to the point where the two 85 bores 2 and 3 of the cylinder unite and communicating with the chamber 3 or bore of greatest diameter is formed an air-port 5, which not only admits atmospheric air back of the shoulder of the differential piston, but 90 also provides for the escape of any leakage from the opposite end of the piston.

6 indicates an annular groove or channel formed on the interior of the cylinder about midway of the length of its greater bore 3, of 95 such width as will insure the simultaneous communication therewith of both of the ports or passages of the piston at or about the time

the piston has completed its working stroke, (or blow,) and adjacent thereto toward the end of said bore 3 is a second narrower annular groove or channel 7, provided with the 5 exhaust-port 8, extending through the case or cylinder 1.

The tool end of the cylinder is preferably threaded on its interior and closed by means of an annular plug 9, contracted at its inner 10 end by an annular inwardly-projecting shoulder 9^a, in which is inserted a movable block or button 10, which receives the impact of the piston, and within said annular plug 9, which closes the end of the cylinder 1, is inserted a bushing or ferrule 11, which not only 15 confines and limits the movement of the block or button 10 when struck by the piston, but also serves to hold the "rivet-set" or tool proper, which is in service.

20 In order to secure the annular end plug 9 against rotation, it is provided with a spring-pressed dog or latch 12, which engages a notch in the end of cylinder 1, the dog or latch being limited in its outward movement 25 by a pin 12^a or equivalent means.

The block or button 10 is movably fitted within the annular flange or shoulder 9^a of end plug 9, so as to transmit the blow of the piston to the tool proper; but the fit is sufficiently tight to prevent any appreciable escape of air from the cylinder 3 below the piston for a short period or until the piston in its return movement has unclosed the exhaust-port 8 of the cylinder.

35 13 indicates the differential piston (or hammer)—that is to say, a piston corresponding in its respective diameters to the bores 2 and 3 of the cylinder 1, its opposite heads being of different area. That head of the piston 40 toward the induction-port 4 is provided with a passage 14, which preferably extends inwardly substantially half the length of the piston and connects with a transverse port or passage 14^a, which opens on the periphery of the piston, while the opposite (or operative) 45 head of the piston is provided with a similar passage 15, which extends inwardly preferably less than half the length of the piston and opens into a transverse passage 15^a, 50 which also opens on the periphery of the piston, the two transverse ports 14^a and 15^a being in adjacent planes or so arranged that they shall both connect with the annular groove 6 of the cylinder 1 when the piston has 55 completed its operative (blow) stroke. As the port or passage 15 opens on the operative face of piston 13 it is preferably eccentrically placed, while, if desired, the passage 14 may be located in the axial line of the piston.

60 The construction of the devices being substantially such as hereinbefore pointed out will operate as follows: The throttle-valve to be operated to admit the fluid-pressure to the cylinder through induction-port 4, the pressure 65 sure will act upon that end of the piston 13 (to

the right of the drawings) having the lesser area, imparting to the piston its working movement, the piston being moved in one direction (to the left in the drawings) until it strikes the block or button 10 and imparts 70 the blow to the tool proper held in the bushing or ferrule 11. By the time the piston has completed its stroke in the given direction (to the left in the drawings) the transverse ports or passages 14^a and 15^a are in register 75 with the annular groove or channel 6, the piston in the meantime having passed over annular groove or channel 7 and closed the exhaust-port 8. The motive fluid passes by passages 14 14^a, channel 6, and passages 15^a 80 15 to the opposite end of the cylinder, where, acting on that head of the piston having the greatest area, a reverse or return movement is imparted to the piston, which ultimately carries the piston-passages 14^a 15^a out of register with the channel 6 and simultaneously opens exhaust-port 8, whereupon the pressure on the opposite or smaller end of the piston repeats the working stroke thereof. The several steps above noted are successively repeated until such time as the throttle-valve is moved to cut off the flow of motive fluid to the cylinder through the induction-port 4 and put the tool out of action.

Having thus described my invention, what 95 I claim, and desire to secure by Letters Patent, is—

1. In a motive-fluid-operated tool, the combination with a suitable cylinder provided with an exhaust-port of a differential piston 100 having separate ports or passages leading from its opposite ends to its periphery at adjacent points, said cylinder having a supply-port arranged to maintain constant pressure on that head of the piston having the lesser 105 area, substantially as and for the purposes specified.

2. In a motive-fluid-operated tool, the combination with a cylinder having a differential bore, an exhaust-port, a motive-fluid-supply 110 port, and an annular groove on its interior at its greatest diameter, of a differential piston having ports or passages leading from its opposite ends to its periphery in adjacent planes and adapted to simultaneously register with 115 the annular groove of the cylinder, substantially as and for the purposes specified.

3. In a motive-fluid-operated tool, the combination with a cylinder having a differential bore provided with an annular groove at its 120 greatest interior diameter, an exhaust groove and port adjacent thereto, and a motive-fluid-supply port, of a differential piston having ports or passages leading from its opposite ends to points on its periphery, the motive-fluid-supply port being arranged to maintain constant pressure on that head of the piston having the lesser area, substantially as and for the purposes specified.

4. In a motive-fluid-operated tool, the com- 125

bination with a piston and its cylinder, of an annular end plug having an annular flange or shoulder on its interior, a ferrule or bushing, and a block or button interposed between 5 the piston and ferrule or bushing, substantially as and for the purposes specified.

In testimony whereof I affix my signature,

in presence of two witnesses, this 27th day of January, 1900.

CHARLES HARRIS JOHNSON.
